UNITED STATES PATENT OFFICE.

CHESTER A. BELL, OF FOREST HILLS, MASSACHUSETTS.

DOOR-OPERATING MECHANISM.

No. 820,949.

Specification of Letters Patent.

Patented May 22, 1906.

Application filed October 18, 1905. Serial No. 283,252.

To all whom it may concern:

Be it known that I, CHESTER A. BELL, a citizen of the United States, residing at Forest Hills, in the county of Suffolk and State of Massachusetts, have invented new and useful Improvements in Door-Operating Mechanism, of which the following is a specification.

This invention relates to improved means for opening and closing doors of the sliding type, more particularly car-doors, although this device is applicable in connection with doors in structures other than cars.

The object of this invention is to provide means whereby the motive power for the propulsion of the car—such, for instance, as electricity—may be utilized for actuating the car-door-operating mechanism, although the device of this invention is equally applicable to cars having means of propulsion other than electricity, in which case batteries may be used to furnish the power for operating said device.

Another object of this invention is to provide means whereby the door may be operated in its opening and closing movements by a brakeman or other person stationed at a point distant from the door.

Another object of this invention is to provide means whereby said door may be locked in its closed position and also in its opened position.

Another object of this invention is to provide means whereby the door at the end of each movement acts to cut off the power which moves said door.

Still another object of this invention is to provide means whereby the motor which moves the door may continue to rotate after the door has come to a state of rest.

The invention consists in the combination and arrangement of parts set forth in the following specification and particularly pointed out in the claims thereof.

Referring to the drawings, Figure 1 is a side elevation of a portion of a car-body, showing my improved door-operating mechanism in connection therewith. Fig. 2 is a detail sectional elevation of a circuit-breaker operated by the door. Fig. 3 is a section, partly in elevation, on line 3-3 of Fig. 1 looking to the left in said figure. Fig. 4 is an electrical diagram, showing the method of wiring, the parts being shown in the proper positions to open the door. Fig. 5 is an electrical diagram, showing the method of wiring,

with the parts in the proper positions to close the door. Fig. 6 is a detail elevation of a modified form of door-lock. Fig. 7 is a detail elevation of another modified form of door-lock. Fig. 8 is a detail elevation of still another modified form of door-lock.

Like numerals refer to like parts throughout the several views of the drawings.

In the drawings, 10 is a car-body of usual construction, in which 11 is a sliding door located on the side of said car-body and provided with a rack 12, fast to its upper edge. The door 11 is operated in its opening and closing movements by means of a pinion 13, loosely mounted upon a motor-shaft 14. An electric motor 15 is mounted upon the car-body 10 and is adapted to rotate the pinion 13 through the medium of a friction-clutch 16, in which 17 is a leather-faced disk fast to the motor-shaft 14 and 18 is a disk fast to the pinion 13, said disk 18 being held in engagement with the disk 17 by means of a helical compression-spring 19, bearing at one end against the pinion 13 and at the other end against a collar 20, fast to the motor-shaft 14. The electric motor 15 receives its power from any suitable source, which may be the same as that which supplies the power to the propelling-motors of the car or from a battery.

A pole-changer 21 of well-known construction conveniently located is adapted to control the motor 15. Said pole-changer 21 when in the position shown in Fig. 4 is adapted to direct the current to the motor 15 and cause the motor-shaft 14 to rotate in the proper direction to open the door 11. When the pole-changer 21 is in the position shown in Fig. 5, it is adapted to send the current to the motor 15 and to rotate the motor-shaft 14 in the proper direction to close the door 11. The pole-changer 21 when in its mid-position cuts off the entire system from the source of electrical current.

Fast to the upper edge of the door 11 and at the right-hand side thereof, Fig. 1, is an incline 22, terminating at its left-hand end in a vertical surface 23, which forms a stop, against which bears a latch 24 when the door 11 is in its closed position. Formed integral with the latch 24 is an armature 25, pivoted at 26 to a bracket 27, mounted upon the car-body 10. An electromagnet 28, also mounted upon the bracket 27, controls the armature 25 and is adapted to lift said armature 25 and withdraw the latch 24 from engagement with the stop 23. Fast to the upper

edge of the door 11 and at the left-hand side thereof is an incline 23, terminating at 30 in a vertical surface, which forms a stop adapted to engage a latch 31 when the door is in its opened position, as shown in dotted lines, Fig. 1. Formed integral with the latch 31 is an armature 32, pivoted at 33 to a bracket 34, fast to the car-body. An electromagnet 35 is also mounted upon the bracket 34 and is adapted to raise the armature 32 and withdraw the latch 31 from engagement with the stop 30.

A circuit-breaker 36 is adapted to be operated by the right-hand edge 37 of the door 11 at the end of the closing movement of said door. A circuit-breaker 38 is adapted to be operated by the left-hand edge 39 of the door 11 at the end of its opening movement. The circuit-breaker 36 consists of a plate 40, upon which is mounted a terminal 41, insulated therefrom. A terminal 42 is fast to a spring 43, said spring 43 being mounted upon the plate 40 and insulated therefrom. Said spring 43 normally acts to hold the terminal 42 in contact with the terminal 41. A pin 44, fast to the spring 43, is adapted to engage the right-hand edge 37 of the door 11, thereby separating the terminal 42 from the terminal 41 when the door 11 is in its closed position. When the door edge 37 is out of engagement with the pin 44, the spring 43 acts to bring the terminal 42 in contact with the terminal 41. The circuit-breaker 38 is identical in construction and operation with the circuit-breaker 36 and consists of a plate 45, a terminal 46, a terminal 47, a spring 48, and a pin 49.

Referring to Figs. 4 and 5, the motor 15, circuit-breaker 36, electromagnet 28, circuit-breaker 38, electromagnet 35, and pole-changer 21 are all represented by conventional signs. The source of electrical current for driving the motor 15 is represented in Figs. 4 and 5 by a well-known conventional sign.

The operation of the device is as follows: Starting with the door 11 in its closed position, a brakeman or other person stationed at the pole-changer 21 moves said pole-changer to the position shown in Fig. 4, thereby directing the current to the magnet 28, thus energizing said magnet and raising the armature 32, thereby withdrawing the latch 31 from engagement with the stop 23, thus unlocking the door 11. Simultaneous with the energizing of the magnet 28 the current passes to the motor 15 and starts said motor to rotate. Should the motor-shaft 14 begin to rotate before the magnet 28 has 60 acted to unlock the door 11, the friction-clutch 16 will permit a slipping action to take place between the two members thereof until the latch 31 is withdrawn from the stop 23, whereupon the motor 15 will rotate the pinion 13 and open the door 11. When the

door 11 is fully opened, it strikes a stop 50, and simultaneously strikes the pin 49 of the circuit-breaker 38, thereby separating the two terminals 47 and 46 and breaking the circuit, thus stopping the motor 15. In the brief 70 interval of time intervening between the breaking of the circuit and the stopping of the motor-shaft 14 the friction-clutch 16 permits a slipping action to take place between the members thereof. At the end of the 75 opening movement of the door 11 the latch 31 rides up the incline 23 and drops behind the stop 30, thereby locking the door 11 in its opened position.

Referring to Figs. 1 and 5, starting with 80 the door 11 open, as shown in dotted lines in Fig. 1, the brakeman or other person moves the pole-changer 21 to the position shown in Fig. 5, thus closing said door in a manner similar to the opening of said door, as hereinbefore described. Should it be desired to stop the door 11 during its opening movement or during its closing movement, the pole-changer 21 may be moved to its mid-position, thereby cutting off the supply of 90 current from the motor 15 and bringing the door 11 to a state of rest.

In Fig. 6 I have illustrated a modified arrangement of the magnet 28, the armature 32, and the latch 31, in which the armature 95 32' is made a separate element from the latch 31 and is connected thereto by a link 57.

In Fig. 7 I have illustrated another modified form of lock in which I employ a solenoid 52 in place of the magnet 28 and a vertically-movable locking-bar 53, suspended upon a helical extension-spring 54. It will be evident that the solenoid 52 will act in a similar manner to the magnet 28 to withdraw the locking-bar 53 from engagement 105 with the stop 23. After the door 11 has passed from beneath the locking-bar 53 and after the solenoid 52 has become deenergized the weight of the locking-bar 53 will be carried by the spring 54, which is attached to the car-body 10.

In Fig. 8 I have illustrated a modified arrangement of the solenoid and latch in which a lock-latch 24' is pivoted at 55 upon the car-body 10 and is connected to the bar 53' by 115 means of a link 56. When the door 11 is withdrawn from beneath the latch 24', the weight of the bar 53', link 56, and latch 24' is carried by the spring 54.

It will be evident that all of the modified 120 forms illustrated in Figs. 6, 7, and 8 will operate equally as well as the arrangement of the electromagnet and latch shown in Fig. 1, and I do not desire to limit myself to the latter construction.

Having thus described my invention, what I claim, and desire by Letters Patent to secure, is—

1. In a door-operating mechanism, a slide- 125 able door, a rack fast thereto, a pinion mesh-

ing into said rack, an electric motor adapted to rotate said pinion, a source of electrical current to drive said motor, an electromagnet in circuit with said electric motor and said source of electrical current, an armature, a door-latch operatively connected to said armature, said door-latch being adapted to lock said door and said armature being adapted to unlock said latch from said door, a pole-changer in circuit with said electric motor, said source of electrical current and said electromagnet, whereby said electromagnet may be operated to unlock said door and whereby said electric motor may be operated to rotate said pinion and to move said door, and two circuit-breakers also in said circuit, one of said circuit-breakers adapted to be operated by said door at the end of its opening movement and the other of said circuit-breakers adapted to be operated by said door at the end of its closing movement.

2. A door-operating mechanism comprising in its construction a slidable door, a rack fast thereto, a pinion meshing into said rack, a motor adapted to rotate said pinion, a source of electrical current to drive said motor, a manually-operatable pole-changer in circuit with said motor and said source of electrical current, an electromagnet also in said circuit, an armature, a door-latch, said armature operatively connected to said door-latch, and two circuit-breakers also in said circuit, one of said circuit-breakers adapted to be operated by said door at the end of its opening movement, the other of said circuit-breakers adapted to be operated by said door at the end of its closing movement.

3. In combination a slidable door, means electrically operated for opening and closing said door, locking means whereby said door may be automatically locked in its closed position, locking means whereby said door may be automatically locked in its opened position, and electrical means, manually operable, whereby said opening and closing means may be controlled and whereby each of said locking means may be actuated to unlock said door.

4. In combination a slidable door, means electrically operated for opening and closing said door, locking means whereby said door may be locked in its closed position, locking

means whereby said door may be locked in its opened position, electrical means, manually operable, whereby said opening and closing means may be controlled and whereby each of said locking means may be actuated to unlock said door, circuit-breaking means automatically operated by said door at the end of its opening movement, and circuit-breaking means automatically operated by said door at the end of its closing movement, each of said circuit-breaking means acting to stop said opening and closing means.

5. In a door-operating mechanism, a slid- 65 able door, a rack fast thereto, a pinion meshing into said rack, an electric motor adapted to rotate said pinion in opposite directions and open or close said door, respectively, and a friction-clutch interposed between said electric motor and said pinion.

6. In a door-operating mechanism, a slid- 75 able door, a rack fast thereto, a pinion meshing into said rack, an electric motor adapted to rotate said pinion, a friction-clutch inter- 80 posed between said electric motor and said pinion said motor being adapted to rotate said pinion in opposite directions and open or close said door, respectively, a latch acting to hold said door in its closed position, and a latch acting to hold said door in its opened position.

7. In a door-operating mechanism, a slid- 85 able door, a rack fast thereto, a pinion meshing into said rack, an electric motor adapted to rotate said pinion in opposite directions and open or close said door, respectively, a latch acting to hold said door in its closed position, a latch acting to hold said door in its opened position, two armatures, one of said 90 armatures operatively connected to said first-named latch, the other of said armatures operatively connected to said second-named latch, and two electromagnets, each of said electromagnets acting to disengage its respective latch from said door.

In testimony whereof I have hereunto set my hand in presence of two subscribing witnesses.

CHESTER A. BELL.

Witnesses:

CHARLES S. GOODING,
ANNIE J. DAILEY.
